US0D1112168S

(12) **United States Design Patent** (10) **Patent No.:** **US D1,112,168 S**
(45) **Date of Patent:** **** Feb. 10, 2026**

(54) **ELECTRONIC DEVICE**

(71) Applicant: **Samsung Electronics Co., Ltd.**,
Suwon-si (KR)

(72) Inventors: **Jaeneung Lee**, Suwon-si (KR);
Chul-Yong Cho, Suwon-si (KR);
Dianaminsun Kang, Suwon-si (KR)

(73) Assignee: **SAMSUNG ELECTRONICS CO., LTD.**, Gyeonggi-Do (KR)

(**) Term: **15 Years**

(21) Appl. No.: **29/846,385**

(22) Filed: **Jul. 15, 2022**

(30) **Foreign Application Priority Data**

Jan. 18, 2022 (KR) 30-2022-0002334
(51) **LOC (15) Cl.** **14-01**

(57) **CLAIM**

The ornamental design for an electronic device, as shown
and described.

DESCRIPTION

FIG. 1 is a front perspective view of an electronic device,
showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a rear perspective view thereof;
FIG. 9 is a perspective view thereof in an alternate position;
and,
FIG. 10 is another front view thereof in an alternate position.
The broken lines illustrating portions of the electronic
device form no part of the claimed design.

1 Claim, 10 Drawing Sheets
